SPONGE WASHER

Walter E. Harvie, Portland, Maine

Application May 31, 1932. Serial No. 614,561

2 Claims. (Cl. 15—130)

The object of this, my present invention, is the provision of a sponge washer that is characterized by simplicity in construction and reliability and efficiency in practical use.

5 To the attainment of the foregoing the invention consists in the improvement hereinafter described and definitely claimed.

In the drawing:

10 Figure 1 is an approximately central longitudinal sectional view through the improvement.

Figure 2 is a side elevation thereof.

15 Figure 3 is a bottom plan view of the sponge holder with the sponge removed.

My improved sponge washer is primarily designed for use in cleaning automobiles and is of a construction whereby every part or crevice of such machines may be cleaned without liability of scratching or marring the surface thereof. The improvement is not to be thus restricted in 20 its useful capacity as the same may be successfully employed for washing windows either on the ground floor or at an elevation, for washing woodwork, bathtubs, etc.

The improvement essentially comprises a rubber handle 1 provided at one of its ends and a point adjacent such end with outwardly extending beads 2, the said beads affording the handle with gripping surfaces. The handle has one end terminating in an elliptical hollow head 3. The hollow head 3 is substantially oval in plan, the open or mouth end thereof being formed with an inwardly directed lip 4, and the said lip is formed with spaced inwardly directed and angularly disposed prongs 5, like prongs 6 being formed on 30 the concaved inner sides of the head. All of the prongs are directed toward the upper center of the head, and the said prongs serve as impinging elements for the portion of a sponge 7 which is inserted in the head. The part of the sponge 35 that is received in the head is cemented to the said head so that after manufacture the handle and sponge will become integral parts and by both cementing and impinging the sponge in the head the same cannot be dislodged therefrom regardless of pressure which is exerted upon the 40 outer or active surface of the sponge or the water which passes through the handle and through the pores of the sponge.

The handle 1 is provided with a round central 45 opening that receives therein one end of a copper pipe 8. The lower end of the pipe is flared or tapered outwardly so that the said pipe is revolvably mounted on the device. The outer right-angular end 9 of the pipe is bent to provide the 50 same with an angular portion 9' which is directed

away from the head 3 over the portion 9 of the pipe 8 and is inserted in a rubber tube 10. The tube is coupled to a hose which in turn is connected to a suitable source of water supply and the passage through the hose is controlled by a 60 valve (not shown). Arranged around the tube 10 to grippingly engage therewith and compress the same against the part 9' there is a clamp 11. The clamp 11 is preferably constructed from a single piece of suitable metal having its central portion 65 rounded upon itself to grippingly engage with the rubber tube and having its parallel depending portions 12 provided with openings for the reception of binding elements such as screws 13. The sides 12 are rounded outwardly away from each 70 other and are suitably secured to a socket 14 which is tapered and which has its outer widened and open end provided with a bayonet slot 15 for the reception of a pin 16 on the tapered end of a handle 17. The handle is preferably in the nature 75 of a wooden stick. The metal socket 11 has its reduced end formed with a tongue extension 18 designed to be received in a hollow boss 19 that extends from one side of the handle 1. Removable means, such as short screws 20 hold the tongue 80 in the boss. Because of its shape the sponge can reach all corners or crevices on surfaces to be cleaned. The supply of water passing through the sponge is regulated by the valve for the hose. Because of the rubber tube 10 the device is rendered 85 flexible and light and this tube serves as one of the handles of the improvement. The handle 1 is also employed as a gripping element for manipulating the device and the removable clamp and socket connected with the handle materially reinforces these parts. The wooden handle 17 is employed when high places are to be washed. The handle 17 is thus in the nature of a prop and will permit of the device being employed in washing windows, etc., although the 90 improvement is primarily devised for washing automobiles. When the socket is detached the body of the improvement may revolve upon the pipe 8 so that the sponge may be turned in the cleaning operation and the same may be arranged to operate upon corners or crevices which might be otherwise unobtainable. The sponge may be dipped in either clean water or sapo- 95 neous fluid, in which instance the flow of water through the pipe 8 is shut off.

100 While I have illustrated a satisfactory embodiment of my improved device, my features of invention are capable of extended application and I do not wish to be limited to the specific details 105 herein shown and described.

Having described the invention, I claim:

1. A device for the purpose set forth, a handle having a cup-like hollow head whose open end is formed with an inwardly directed lip, said lip being integrally formed with angularly disposed prongs directed toward the top of the head, the inner sides of the head being integrally formed with prongs directed toward the center thereof and said prongs affording impinging elements for 10 a sponge which is inserted in the head and cemented thereto, the handle having outer peripheral ribs and having a central opening, and a fluid conducting tube received in said opening.
2. A device for the purpose set forth, comprising 15 a hollow elliptical head having a beaded mouth which, together with the sides of the head

are formed with inwardly projected prongs to engage with a sponge which is inserted in the head, a hollow handle extension on the head, a water conducting pipe received in the extension, said pipe having an angle extension affording a hand grip, a water conducting tube on the pipe, a clamping member removably engaging with the tube for clamping the same on the pipe, a socket carried by said clamping member having an inner closed end provided with a tongue extension, a hollow boss on the handle receiving the tongue extension therein, removable means for securing the tongue extension in the boss and said socket designed for the reception of a handle which may be employed as a prop. 80 85 90
